[57] CLAIM

The ornamental design for a covered bowl, as shown and described.

DESCRIPTION

FIG. 1 is a front elevational view of a covered bowl showing my new design, the rear view being identical;

FIG. 2 is a left side elevational view thereof, the right side view being a mirror image;

FIG. 3 is a top view thereof; and

FIG. 4 is a bottom view thereof.

FIG. 2.

FIG. 3.FIG. 4.
